Primary Examiner — Barbara Fox*Assistant Examiner* — Lilyana Bekic*(74) Attorney, Agent, or Firm* — James P. Riek(57) **CLAIM**

The ornamental design for an inhaler device, as shown and described.

DESCRIPTION

FIG. 1 is a front, top and side perspective view of an inhaler device in a closed configuration according to the new design;

FIG. 2 is a top plan view of the inhaler device;

FIG. 3 is a bottom plan view of the inhaler device of FIG. 1;

FIG. 4 is a side view of the inhaler device of FIG. 1;

FIG. 5 is an opposite side view of the inhaler device of FIG. 1;

FIG. 6 is a rear, and side perspective view of the inhaler device of FIG. 1;

FIG. 7 is a front view of the inhaler device of FIG. 1;

FIG. 8 is a rear view of the inhaler device of FIG. 1;

FIG. 9 is a front, top and side perspective view of the inhaler device of FIG. 1 shown in an open configuration;

FIG. 10 is a top plan view of the inhaler device of FIG. 9;

FIG. 11 is a bottom plan view of the inhaler device of FIG. 9;

FIG. 12 is a side view of the inhaler device of FIG. 9;

FIG. 13 is an opposite side view of the inhaler device of FIG. 9;

FIG. 14 is a rear, bottom and side perspective view of the inhaler device of FIG. 9;

FIG. 15 is a front view of the inhaler device of FIG. 9; and,

FIG. 16 is a rear view of the inhaler device of FIG. 9.

The broken lines in the drawings illustrate portions of the inhaler device which form no part of the claimed design.
